CLOCK

Charles A. McLeod, Oak Park, Ill., assignor to Sunbeam Corporation, Chicago, Ill., a corporation of Illinois

Filed Dec. 29, 1964, Ser. No. 83,209

Term of patent 14 years

(Cl. D42—7)

FIG. 1 is a front elevational view of a clock, showing my design;

FIG. 2 is a top plan view thereof; and

FIG. 3 is an enlarged sectional view taken along line 3—3 of FIG. 1.

I claim:

The ornamental design for a clock, as shown.

Home Furnishings Daily, Mar. 10, 1958, page 5: clock 3585.

Jewelers' Circular-Keystone, August 1956, page 207: clock 3281.

Office Appliances, April 1958, page 44: clock 3.

EDWIN H. HUNTER, Primary Examiner.
